Company, Swissvale, Pa., a corporation of Penn-
sylvania

Application August 17, 1938, Serial No. 225,372

20 Claims. (Cl. 246—46)

Our invention relates to railway signalling systems of the type employing light signals wherein the signals each comprise a plurality of lamps, and wherein when one lamp of a signal becomes burned out another lamp of that signal will become lighted to cause the signal to display a more restrictive indication.

An object of our invention is to provide an improved signal system of the type described and 10 wherein a distinctive permissive indication is displayed at the entrance to an occupied block so that a train may enter such block without stopping, and wherein a stop indication is displayed if the permissive indication is not displayed when 15 it should be.

A further object of our invention is to provide a system of the type described and in which if the lamp of the clear signal becomes burned out the lamp for giving a restrictive proceed indication will automatically be lighted in its place.

Another object of our invention is to provide a signal system of the type described and in which a plurality of lamps are employed to provide the permissive signal at the entrance of an occupied block, and which system is arranged so that if either of the lamps for giving the permissive indication is burned out the stop indication will be displayed.

A further object of our invention is to provide an improved signal system of the type described.

Other objects of our invention and features of novelty will be apparent from the following description taken in connection with the accompanying drawings.

We shall describe one form of apparatus embodying our invention and shall then point out the novel features thereof in claims.

In the accompanying drawings Figs. 1A and 1B taken together form a diagram illustrating a 40 system embodying our invention.

Referring to the drawings, the reference numerals 1 and 2 designate the rails of a stretch of railway track over which traffic normally moves in the direction indicated by the arrows. The 45 rails 1 and 2 are divided by insulated joints 3 into a plurality of track sections or blocks W—X and X—Y. Each section is provided with a track battery 5 connected across the rails adjacent the exit end of the section, and with a track relay 50 which is connected across the track rails adjacent the entrance end of the section.

Each of the track relays is identified by the reference character TR together with a prefix the same as for the signal for the section with 55 which the track relay is associated.

Located adjacent the entrance end of each section is a signal. The signals are designated by the reference characters 10S, 11S and 12S. As herein shown, each signal includes a proceed lamp G capable of displaying a green light, an upper yellow lamp Y capable of displaying a yellow light, a red lamp R capable of displaying a red light, and a lower yellow lamp Y capable of displaying a yellow light.

Each signal has associated therewith in addition to a track relay TR, a distant relay DR, an approach lighting relay AR, a first lightout relay LOR, a second lightout relay ZR, a transfer relay SR, and a source of energy in the form of a battery D.

The distant relay DR associated with each signal has one terminal of its winding connected to a branch of a wire 20 leading to a common line CL which parallels the track stretch, while the wire 20 is also connected to a terminal of the 20 battery D at that signal location. The other terminal of the winding of the relay DR associated with each signal is connected by a wire 58 to a movable contact 55 of the track relay TR associated with the same signal, and when this contact 25 is picked up it engages a stationary contact to which is connected a wire 48 leading to the terminal of the winding of the approach lighting relay AR associated with the adjacent signal in advance. The other terminal of the winding of 30 the approach lighting relay AR associated with each signal is connected by a circuit which is controlled by the contact 35 of the track relay for that signal to a wire 21 which is connected to a terminal of the battery D at the signal location 35 at which the approach lighting relay AR is located.

It will be seen, therefore, that the winding of approach lighting relay AR at each signal is connected to the battery at that signal in series 40 with the relay DR associated with the adjacent signal in the rear, and that this circuit is controlled by the track relay associated with the signal with which the approach lighting relay is associated and also by the track relay associated 45 with the signal of the adjacent block section in the rear.

The approach lighting relay AR for each signal controls a circuit from which current is supplied to the yellow and green lamps for that signal, 50 while the distant relay DR selectively controls the supply of current to the green and the upper yellow lamps of the signal with which the relay is associated. The relay DR also controls the circuit of the transfer relay SR, while the circuit 55

of the relay SR is further controlled by the relay ZR.

The lightout relay LOR operates to establish a circuit to the upper yellow light in the event 5 that the green lamp is not lighted at a time at which it should be.

The transfer relay SR controls the circuits of the two yellow lamps and also controls a circuit for energizing its own winding, while the track 10 relay TR for each section governs circuits for energizing both the upper and lower yellow lamps of the signal for that section.

Each of the relays ZR has a pair of windings, 15 one of these being constantly connected in series with the lower yellow lamp, and the other being at times connected in series with the energizing circuit of the upper yellow lamp. The windings of each of the relays ZR are wound in opposition and are arranged so that when both are energized 20 the contact of the relay will remain released, but so that if either winding is energized at a time when the other winding is not energized the relay contact will be picked up.

Having thus described in general the apparatus 25 shown in the drawings, we shall now describe its operation.

When a train is in a block section the track relay TR of the adjacent signal in the rear (see signal 12S) is deenergized and its contacts engage 30 their back points of contact to establish circuits to light both yellow lamps in series with the windings of the relay ZR, which circuits are also controlled by the contact of the approach lighting relay AR associated with the signal.

35 When the track relay at a signal is released the circuit of the approach lighting relay at that signal is interrupted, thereby completing the circuits to the yellow lamps at that signal, while the relay DR of the adjacent signal in the rear is deenergized as it is connected in series with the approach lighting relay AR.

When the relay DR is deenergized and the track relay is energized (see signal 11S), which is the condition when there is only one clear block in 45 advance of a signal, a circuit is established to light only the lamp of the upper yellow lamp, the circuit not being complete, however, until the approach lighting relay associated with that signal becomes released.

50 When the track relays at a signal and at the adjacent signal in the rear are both energized, that is when there are two clear blocks in advance of a signal, the circuit of the approach lighting relay AR at that signal and of the relay DR of the adjacent signal in the rear is complete with the result that these relays are both energized.

When the relay DR is energized (see signal 10S) 55 a circuit is established to supply current to the green lamp G of the signal with which the relay DR is associated, this circuit not being completed, however, until the approach lighting relay AR at that signal is released.

A train K is here shown diagrammatically at the right of location Y so that the track relay 60 12TR is deenergized with the result that its contacts 25 and 26 engage their back points of contact and establish connections from wire 27 to light the lamps of both the upper and lower yellow lights of the signal 12S to indicate that the block 65 section in advance of the signal is occupied.

The circuit for energizing the upper yellow lamp Y includes wire 27, back point of contact 25 of relay 12TR, wire 28, lower winding 30 of relay 12ZR, and wire 31 to a terminal of the upper 70 yellow lamp Y, the other terminal of which is

connected by a wire 32 to a front point of contact of relay 12SR. At this time the relay 12SR is energized and its contact 33 establishes a circuit to wire 31 from a branch of wire 28 which is connected to a terminal of the battery 12D. 5

The circuit for energizing the lower yellow lamp Y includes wire 27, contact 26 of relay 12TR, wire 38, upper winding 40 of relay 12ZR, and wire 41 which is connected to a terminal of lower yellow lamp Y, the other terminal of which is connected 10 by wire 32 to wire 28 and thus to a terminal of the battery 12D.

As the track relay 12TR is released due to the presence of a train in the section at the right of location Y, contact 35 of relay 12TR is released, 15 thereby interrupting the circuit from wire 21, which is connected to a terminal of battery 12D, to wire 36, which leads to a terminal of the winding of the approach relay 12AR. The winding of the approach lighting relay 12AR, therefore, is 20 deenergized and its contact 52 engages its back point of contact to complete a circuit from wire 21, leading from the battery 12D, to wire 27 which is connected to the movable contacts 25 and 26 of relay 12TR. The circuit for supplying current to 25 the upper and lower yellow lamps of signal 12S, therefore, is complete and these lamps are lighted.

As long as the filaments of both lamps remain intact current continues to flow in the circuits of these filaments, and also in the windings 30 and 35 40 of relay 12ZR, with the result that these windings are both energized and the contact 43 of this relay remains in its released position and maintains the circuit from a branch of wire 20, leading from a terminal of the battery 12D, to the wire 44 35 which is connected to one terminal of the winding of the relay 12SR.

At this time the circuit from the other terminal of the battery 12D to the other terminal of the winding of the relay 12SR is maintained through 40 the wire 21 and a contact 45 of the relay 12SR.

As the contact 35 of relay 12TR is open the circuit of which the wire 48 leading from a terminal of the approach lighting relay 12AR to the winding of the relay 11DR forms a part is interrupted and the relay 11DR is released with the result that its contact 50 engages its back point of contact. The section X—Y being unoccupied, the track relay 11TR of this section is energized with the result that its contacts 25 and 26 are picked 50 up and do not establish the circuits leading to the upper and lower yellow lamps.

Since the track section X—Y is not occupied, the track relay 11TR is energized, and as the contact 25 of track relay 11TR is picked up it completes a circuit from wire 27 to wire 49, one branch of which is connected through back point of contact 50 of relay 11DR to a branch of wire 31 leading to one terminal of the upper yellow light Y. 60

At this time the approach lighting relay 11AR is energized in a manner hereinafter explained in detail and its contact 52 is picked up and interrupts the connection of wire 27 to wire 21 leading from the battery 11D. Accordingly, even though 65 contact 25 of 11TR is picked up and connects wires 27 and 49, the wire 49 is not energized. Energization of wire 49 does not take place until a train enters block section W—X and causes the release of approach lighting relay 11AR. 70

When this occurs the circuit to the upper yellow lamp is completed and may be traced from one terminal of the battery 11D through wire 21, contact 52 of relay 11AR, wire 27, contact 25 of relay 11TR, wire 49, contact 50 of relay 75

11DR, wire 31, upper yellow lamp Y, wire 32, contact 33 of relay 11SR, and wire 20 to the other terminal of the battery 11D. When a train enters the block section W-X, therefore, and releases approach lighting relay 11AR, the upper yellow lamp of the signal 11S will be lighted to give the approach indication.

As the track relay 10TR is energized its contact 35 is picked up and connects wire 21, leading from a terminal of battery 10D, to wire 36 leading to a terminal of the winding of approach lighting relay 10AR. The other terminal of this winding is connected by wire 48 to a stationary contact of track relay 10TR. The contacts of 10TR are picked up at this time as the track section W-X is assumed to be unoccupied. The contact 55 of relay 10TR accordingly connects wire 48 to wire 56 leading to one terminal of the winding of relay 10DR. The other terminal 20 of the winding of relay 10DR is connected by a branch of wire 20 to the common line CL and thereby to the battery 11D at signal 11S. A circuit is accordingly established to energize in series the approach lighting relay 11AR associated with signal 11S, and the relay 10DR associated with the signal 10S with current supplied from the battery 11D associated with the signal 11S.

As relay 10DR is energized its contact 50 is picked up and connects wire 49 to wire 60 which is connected in series with the winding of the relay 10LOR to a terminal of the green lamp G, the other terminal of which is connected by a branch of wire 20 to the battery 10D. At this time as the contacts of relay 10TR are picked up, its contact 25 connects wire 27 to wire 49, but as the approach lighting relay 10AR is assumed to be energized, its contact 52 does not connect wire 27 to wire 21, and thus to a terminal of the battery 10D. The green lamp G of signal 10S is not illuminated as long as approach lighting relay 10AR is energized, but when the track section at the left of signal 10S becomes occupied, relay 10AR will be released and the contact 52 of this relay will complete the circuit to supply current from battery 10D to light the green lamp G to provide the clear indication.

If the filament of the lamp G is intact the current flowing in the circuit of the lamp filament will energize the winding of the relay 10LOR and cause the contact 62 of this relay to be picked up, thereby interrupting connection between a branch of wire 49 and a branch of wire 31 leading to the upper yellow lamp.

At this time the contacts of track relay 10TR are picked up and its contact 25 connects wire 27 to wire 49 with the result that when the contact 52 of approach lighting relay 10AR is released wire 49 is connected to wire 21 and thus to one terminal of battery 10D. However, as contact 62 of relay 10LOR is picked up as long as the green lamp G is lighted a circuit is not established from wire 49 to the upper yellow lamp Y while the green lamp remains lighted.

This system is arranged so that if the filament of the green light G becomes burned out and fails to provide a signal indication when current is supplied to the circuit of the lamp filament, the upper yellow lamp will automatically be lighted to give an approach indication instead of a clear indication.

Thus it will be seen that if the filament of the green lamp G should become burned out, thereby breaking the circuit of which the filament forms a part, the winding of the relay 10LOR will be

deenergized and the contact 62 of this relay will be released, thereby completing a circuit from wire 49 to wire 31, and thus to the upper yellow lamp Y to light this lamp. The signal, therefore, will give the approach indication instead of the clear indication.

This system is also arranged so that in the event that the lamp of either of the yellow lights is burned out at a time when both lamps should be lighted, the lamp of the red light will be lighted and the lamp of the other yellow light will be extinguished.

Referring to the signal 12S, it will be seen that the upper yellow lamp Y is energized in series with the winding 30 of the relay 12ZR, while the lower yellow lamp Y is energized in series with the winding 40 of the relay 12ZR. As long as the filaments of both lamps remain intact, both windings of the relay 12ZR are energized and the contact 43 of this relay remains released and maintains the circuit to the winding of the relay 12SR.

If, however, the filament of the lamp of either yellow light should be burned out, the winding of the relay 12ZR which is connected in series with that filament will no longer be energized. The other winding of the relay 12ZR will be energized, however, and will cause the contact 43 of the relay 12ZR to be picked up, thereby interrupting the circuit to the winding of the relay 12SR.

When the winding of the relay 12SR is de-energized the contact 33 of this relay is released, thereby interrupting the connection from wire 20, leading from a terminal of battery 12D, to wire 32 leading to the upper and lower yellow lamps. At this time, therefore, the yellow lamp the filament of which remains intact will be extinguished, while the winding of the relay 12ZR which is connected in series with that lamp filament will be deenergized, thereby releasing the contact 43 of relay 12ZR. The contact 43, when released, will again connect a terminal of the winding of the relay 12SR to the wire 20 and thus to the battery 12D.

However, the circuit of the winding of the relay 12SR is interrupted at another point at this time, and the winding does not become energized when the contact 43 of relay 12ZR is released.

It will be seen that when a train is in the block section at the right of signal 12S, which is the situation when both yellow lamps are intended to be lighted, the relay 12TR is released and its contact 55 interrupts the circuit of the winding of the relay 12DR with the result that the relay 12DR is deenergized. Accordingly, the contact 63 of the relay 12DR is released and does not establish a circuit from wire 21 leading from one terminal of battery 12D to wire 64 leading to a terminal of the winding of relay 12SR.

When the contact 43 of relay 12ZR became picked up and interrupted the circuit to the winding of the relay 12SR, the contact 45 of relay 12SR became released, thereby interrupting the stick circuit from wire 21 to wire 64 leading to a terminal of the winding of relay 12SR. Accordingly, both connections from wire 21 to a terminal of the winding of the relay 12SR are interrupted, and when contact 43 of relay 12ZR becomes released to again establish connection from wire 20 to the other terminal of the winding of the relay 12SR, this winding will not be energized and the contacts of the relay 12SR will remain released.

When the contact 45 of relay 12SR is released it engages its back point of contact and establishes a circuit from wire 21 leading from battery 12D, to wire 66 leading to one terminal of the lamp of the red lamp R, the other terminal of which is connected by a branch of wire 20 to the other terminal of the battery 12D. The lamp R, therefore, becomes illuminated to give a stop signal.

10 In addition, it will be seen that as the contacts of relay 12SR are released its contact 33 interrupts the circuit connecting the upper and lower yellow lamps to one terminal of the battery 12D with the result that neither of these lamps can be energized until the contacts of relay 12SR become picked up.

The relay 12DR, when released, will not become energized until the train K has advanced far enough to leave two clear blocks at the right 20 of signal 12S. When the train advances this far the winding of relay 12DR will become energized over a circuit similar to that traced in connection with relay 10DR. When the relay 12DR is energized its contact 50 establishes a circuit through which current may be supplied to light the lamp of the green light G of signal 12S, while the contact 63 of relay 12DR establishes a circuit from a terminal of the battery 12D through wire 21 to the wire 64 leading to the 30 terminal of the winding of the relay 12SR.

The other terminal of the winding of the relay 12SR is connected by wire 44 and contact 43 of relay 12ZR to the other terminal of the battery 12D and the winding of relay 12SR, therefore, will be energized, and the contact 45 of the relay will be picked up and will complete the stick circuit to the relay winding so that the relay will thereafter remain energized until the contact 43 of relay 12DR again becomes picked 40 up and interrupts the circuit of the winding of the relay 12SR.

When the contact 45 of relay 12SR becomes picked up it interrupts the circuit to wire 66 leading to the red lamp R, thereby extinguishing 45 this lamp.

When the contacts of relay 12SR are picked up the contact 33 of this relay again completes the circuit from a terminal of the battery 12D to wire 32 leading to the upper and lower yellow 50 lamps. However, assuming that the defective lamp of the yellow light has not been replaced, when another train enters the block section at the right of signal 12S and releases the track relay 12TR, the contact 43 of relay 12ZR will again 55 become picked up as only one winding of the relay 12ZR will be energized. When contact 43 is picked up the circuit to the winding of relay 12SR is interrupted and the contact 33 interrupts the circuits of the yellow lamps, while the contact 45 again establishes a circuit to the red lamp.

It will be seen, therefore, that if either of the yellow lamps is burned out so that the normal 60 permissive signal employed at the entrance to an occupied block is not displayed, when it should be, the red lamp will be lighted instead, and will remain lighted until two clear blocks in advance of the signal are provided, whereupon the red lamp will be extinguished, while a circuit is established to energize the green lamp, which circuit however, is not completed until the approach lighting relay is released.

Although we have herein shown and described only one form of apparatus embodying our invention, it is understood that various changes and

modifications may be made therein within the scope of the appended claims without departing from the spirit and scope of our invention.

Having thus described our invention, what we claim is:

1. In combination, a section of railway track, a signal governing traffic in said section, said signal having a pair of lamps each having a filament, said lamps when both illuminated providing one signal aspect, a relay having a pair of windings, and means for energizing the filament of one of said lamps in series with one of said relay windings and for simultaneously energizing the filament of the other of said lamps in series with the other of said relay windings, the relay having a contact which is picked up when and only when one of said relay windings is energized at a time at which the other of said relay windings is not energized, said signal having another lamp energized by a circuit established on picking up of said relay contact. 10

2. In combination, a section of railway track, a signal governing traffic in said section, said signal having a pair of lamps each having a filament, said lamps when both illuminated providing one signal aspect, a relay having a pair of windings, and means for energizing the filament of one of said lamps in series with one of said relay windings and for simultaneously energizing the filament of the other of said lamps in 20 series with the other of said relay windings, the relay having a contact which is picked up when and only when one of said relay windings is energized at a time at which the other of said relay windings is not energized, said signal having 30 associated therewith other indication means controlled by said relay contact. 35

3. In combination, a signal having a pair of lamps each having a filament, said lamps when both illuminated providing one signal aspect, a relay having a pair of windings, means for energizing the filament of one of said lamps in series with one of said relay windings and for simultaneously energizing the filament of the other of said lamps in series with the other of said relay windings, the relay having a contact which becomes picked up when and only when one of said relay windings is energized at a time at which the other of said relay windings is not energized, means operated on picking up of said relay contact for interrupting the circuits for energizing said lamp filaments and said relay windings, and another lamp associated with said signal and energized by a circuit established on picking up of said relay contact. 40

4. In combination, a section of railway track, a signal governing traffic in said section, said signal having a pair of lamps each having a filament, said lamps when both illuminated providing one signal aspect, a relay having a pair of windings, means controlled by traffic conditions in said section for energizing the filament of one of said lamps in series with one of said relay windings and for simultaneously energizing the filament of the other of said lamps 60 in series with the other of said relay windings, the relay having a contact which becomes picked up when and only when one of said windings is energized at a time at which the other of said windings is not energized, whereby said 65 relay contact becomes picked up in the event that the circuit of one relay winding is interrupted as a result of failure of the lamp filament which is connected in series therewith, said signal having associated therewith a third 70 75

- lamp which is supplied with energy by a circuit established on picking up of said relay contact.
5. In combination, a section of railway track, a signal governing traffic in said section, said signal having a pair of lamps each having a filament, said lamps when both illuminated providing one signal aspect, a relay having a pair of windings, means controlled by traffic conditions in said section for energizing the filament of one of said lamps in series with one of said relay windings and for simultaneously energizing the filament of the other of said lamps in series with the other of said relay windings, the relay having a contact which becomes picked up when and only when one of said windings is energized at a time at which the other of said windings is not energized, whereby said relay contact becomes picked up in the event that the circuit of one relay winding is interrupted as a result of failure of the lamp filament which is connected in series therewith, said signal having associated therewith other indication means controlled by said relay contact.
6. In combination, a section of railway track, a signal governing traffic in said section, said signal having a pair of lamps each having a filament, said lamps when both illuminated providing one signal aspect, a relay having a pair of windings, means controlled by traffic conditions in said section for energizing the filament of one of said lamps in series with one of said relay windings and for simultaneously energizing the filament of the other of said lamps in series with the other of said relay windings, the relay having a contact which becomes picked up when and only when one of said windings is energized at a time at which the other of said windings is not energized, whereby said relay contact becomes picked up in the event that the filament of one lamp is defective, thereby interrupting the circuit of one of the relay windings at a time when both windings should be energized, said signal having associated therewith other indication means controlled by said relay contact, and means controlled by traffic conditions in advance of said section for energizing the filament of one of said lamps by means of a circuit shunting the relay winding connected in series with said lamp filament.
7. In combination, a section of railway track, a signal governing traffic in said section, said signal having a pair of lamps each having a filament, said lamps when both illuminated providing one signal aspect, a relay having a pair of windings, means controlled by traffic conditions in said section for energizing the filament of one of said lamps in series with one of said relay windings and for simultaneously energizing the filament of the other of said lamps in series with the other of said relay windings, the relay having a contact which becomes picked up when and only when one of said windings is energized at a time at which the other of said windings is not energized, whereby said relay contact becomes picked up in the event that the filament of one lamp is defective, thereby interrupting the circuit of one of the relay windings at a time when both windings should be energized, said signal having associated therewith other indication means controlled by said relay contact, and means operative in the event of failure of another lamp of said signal for energizing the filament of one of said lamps by means of a circuit shunting the relay winding which is connected in series with said lamp filament.
8. In combination, a section of railway track, a signal governing traffic in said section, said signal having a pair of lamps each having a filament, said lamps when both illuminated providing one signal aspect, a lightout relay having a pair of windings and a contact which is picked up when and only when one of said windings is energized at a time when the other of the windings is not energized, a first supply circuit for energizing one of the windings of the lightout relay in series with the filament of one of the lamps, a second supply circuit for energizing the other of the windings of the lightout relay in series with the filament of the other of said lamps, means controlled by traffic conditions in said section for at times completing both of said supply circuits, a control relay controlled by the contact of the lightout relay and controlling said supply circuits, and other indication means controlled by said control relay.
9. In combination, a section of railway track, a signal governing traffic in said section, said signal having a pair of lamps each having a filament, said lamps when both illuminated providing one signal aspect, a lightout relay having a pair of windings and a contact which is picked up when and only when one of said windings is energized at a time when the other of the windings is not energized, a first supply circuit for energizing one of the windings of the lightout relay in series with the filament of one of the lamps, a second supply circuit for energizing the other of the windings of the lightout relay in series with the filament of the other of said lamps, means controlled by traffic conditions in said section for at times completing both of said supply circuits, a control relay, means controlled by traffic conditions in said section for establishing a circuit from one terminal of a source of current to one terminal of the control relay winding, the control relay having a contact operative when and only when the relay winding is energized to also establish a circuit from said terminal of said source to said terminal of said relay winding, the contact of the lightout relay being operative when and only when released to establish a circuit from the other terminal of the source to the other terminal of the control relay winding, the control relay being operative when its winding is deenergized to interrupt both of said supply circuits, and other indication means controlled by said control relay.
10. In combination, a section of railway track, a signal governing traffic in said section, said signal having a pair of lamps each having a filament, said lamps when both illuminated providing one signal aspect, a lightout relay having a pair of windings and a contact which is picked up when and only when one of said windings is energized at a time when the other of the windings is not energized, a first supply circuit for energizing one of the windings of the lightout relay in series with the filament of one of the lamps, a second supply circuit for energizing the other of the windings of the lightout relay in series with the filament of the other of said lamps, means controlled by traffic conditions in said section for at times completing both of said supply circuits, a control relay, means controlled by traffic conditions in advance of said section for establishing a circuit from one terminal of a source of current to one terminal of the control relay winding, the control relay having a contact operative when and only when released to establish a circuit from the other terminal of the source to the other terminal of the control relay winding, the control relay being operative when its winding is deenergized to interrupt both of said supply circuits, and other indication means controlled by said control relay.

ing a contact operative when and only when the relay winding is energized to also establish a circuit from said terminal of said source to said terminal of said relay winding, the contact 5 of the lightout relay being operative when and only when released to establish a circuit from the other terminal of the source to the other terminal of the control relay winding, the control relay being operative when its winding is de-10 energized to interrupt both of said supply circuits, and other indication means controlled by said control relay.

11. In combination, a section of railway track, a signal governing traffic in said section, said 15 signal having a first, a second, a third and a fourth lamp, said first and second lamps being simultaneously illuminated to provide one signal aspect, a lightout relay having a pair of windings, a first supply circuit for energizing the filament of the first lamp in series with one of said relay windings, a second supply circuit for energizing the filament of the second lamp in series with the other of said relay windings, said 20 relay having a contact which is picked up when and only when one of the relay windings is energized at a time at which the other winding is not energized, means controlled by traffic conditions in said section for at times completing both of said supply circuits to thereby energize 25 said first and second lamps in series with said lightout relay windings, means operative on picking up of the relay contact for energizing the third lamp, whereby said third lamp will become lighted in the event either of said first 30 and second lamps is not lighted when it should be, and means controlled by traffic conditions in advance of said section for at times energizing the fourth lamp and at other times energizing the first lamp by a circuit shunting the relay 35 winding which is connected in series with the filament of said lamp.

12. In combination, a section of railway track, a signal governing traffic in said section, said signal having a first, a second, a third and a fourth lamp, said first and second lamps being simultaneously illuminated to provide one signal aspect, a lightout relay having a pair of windings, a first supply circuit for energizing the filament of the first lamp in series with one of said relay windings, a second supply circuit for energizing the filament of the second lamp in series with the other of the relay windings, said 40 relay having a contact which is picked up when and only when one of the relay windings is energized at a time at which the other winding is not energized, means controlled by traffic conditions in said section for at times completing both of said supply circuits to thereby energize said first and second lamps in series with said 45 lightout relay windings, means operative on picking up of the relay contact for energizing the third lamp, whereby said third lamp will become lighted in the event either of said first and second lamps is not lighted when it should be, means controlled by traffic conditions in advance of said section for at times energizing the fourth lamp and at other times energizing the first lamp by a circuit shunting the relay winding which is connected in series with the filament of said lamp, and means responsive to the flow of current in the circuit of the fourth lamp for controlling means for energizing the first lamp by a circuit shunting the relay winding which is connected in series with said lamp filament.

13. In combination, a section of railway track,

a source of current, a signal governing traffic in said section, said signal having a first, a second, a third and a fourth lamp, said first and second lamps being simultaneously illuminated to provide one signal aspect, a lightout relay 5 having a pair of windings, said relay having a contact which is picked up when and only when one of said relay windings is energized at a time at which the other winding is deenergized, a first supply circuit for energizing the filament of the first lamp in series with one of said relay windings, a second supply circuit for energizing the filament of the second lamp in series with the other of said relay windings, a third supply circuit, means controlled by traffic conditions in said 10 section for at one time establishing connection from one terminal of said source to said first and second supply circuits to thereby energize said first and second lamps in series with said lightout relay windings and for at another time establishing connection from said terminal of said source to said third supply circuit, means operative on picking up of said relay contact for energizing the third lamp, whereby said third lamp will become lighted in the event either of 15 said first and second lamps is not lighted when it should be, and means controlled by traffic conditions in advance of said section for at times establishing connection from said third supply circuit to energize the fourth lamp and at other 20 times to energize the first lamp by means of a circuit which shunts at the relay winding which is connected in series with the filament of said lamp.

14. In combination, a section of railway track, 35 a source of current, a signal governing traffic in said section, said signal having a first, a second, a third and a fourth lamp, said first and second lamps being simultaneously illuminated to provide one signal aspect, a lightout relay 40 having a pair of windings, said relay having a contact which is picked up when and only when one of said relay windings is energized at a time at which the other winding is not energized, a first supply circuit for energizing the filament of the first lamp in series with one of said relay windings, a second supply circuit for energizing the filament of the second lamp in series with the other of said relay windings, a third supply circuit, means controlled by traffic conditions in 45 said section for at one time establishing connection from one terminal of said source to said first and second supply circuits to thereby energize said first and second lamps in series with said lightout relay windings and for at another time establishing connection from said terminal of said source to said third supply circuit, means operative on picking up of said relay contact for energizing the third lamp, whereby said third lamp will become lighted in the event either of 50 said first and second lamps is not lighted when it should be, means controlled by traffic conditions in advance of said section for at times establishing connection from said third supply circuit to energize the fourth lamp and at other 55 times to energize the first lamp by means of a circuit which shunts at the relay winding which is connected in series with the filament of said lamp, and means responsive to flow of current in the circuit of the fourth lamp for establishing 60 connection from the third supply circuit to energize the first lamp by means of a circuit which shunts the relay winding which is connected in series with the filament of said first lamp.

15. In combination, a section of railway track, 75

5 a source of current, a signal governing traffic in said section, said signal having a first, a second, a third and a fourth lamp, said first and second lamps being simultaneously illuminated to provide one signal aspect, a lightout relay having a pair of windings, said relay having a contact which is picked up when and only when one of said relay windings is energized at a time at which the other winding is not energized, a first 10 supply circuit for energizing the filament of the first lamp in series with one of said relay windings, a second supply circuit for energizing the filament of the second lamp in series with the other of said relay windings, a third supply circuit, means controlled by traffic conditions in said section for at one time establishing connection from one terminal of said source to said first and second supply circuits to thereby energize said first and second lamps in series with said lightout relay windings and for at another 15 time establishing connection from said terminal of said source to said third supply circuit, means operative on picking up of said relay contact for energizing the third lamp and for also controlling said first and second supply circuits, 20 whereby said third lamp will become lighted in the event either of said first and second lamps is not lighted when it should be, and means controlled by traffic conditions in advance of said 25 section for at times establishing connection from said third supply circuit to energize the fourth lamp and at other times to energize the first lamp by means of a circuit which shunts at the relay winding which is connected in series with the filament of said lamp.

30 16. In combination, a section of railway track, a source of current, a signal governing traffic in said section, said signal having a first, a second, a third and a fourth lamp, said first and second lamps being simultaneously illuminated to provide one signal aspect, a lightout relay having a pair of windings, said relay having a contact which is picked up when and only when one of said relay windings is energized at a time at which the other winding is not energized, a first 35 supply circuit for energizing the filament of the first lamp in series with one of said relay windings, a second supply circuit for energizing the filament of the second lamp in series with the other of said relay windings, a third supply circuit, means controlled by traffic conditions in said section for at one time establishing connection from one terminal of said source to said first and second supply circuits to thereby energize said first and second lamps in series with said lightout relay windings, and for at another 40 time establishing connection from said terminal of said source to said third supply circuit, means operative on picking up of said relay contact and also controlled by traffic conditions in advance of said section for energizing the third lamp and for controlling said first and second supply circuits, whereby said third lamp will become lighted in the event either of said first and second lamps is not lighted when it should be, and means controlled by traffic conditions in advance of said section for at times establishing connection from said third supply circuit to energize the fourth lamp and at other times to energize the first lamp by means of a circuit which shunts at the relay winding which is connected in series with the filament of said lamp.

45 17. In combination, a section of railway track,

5 a signal governing traffic in said section, said signal having a pair of lamps each having a filament, said lamps when both illuminated providing one signal aspect, a first and a second control winding, means controlled by traffic conditions in said section for energizing one of said lamp filaments in series with one of said control windings and for also energizing the other of said lamp filaments in series with the other of said control windings, said signal having a third 10 lamp, and means controlled by said control windings for controlling the supply of current to said third lamp.

15 18. In combination, a section of railway track, a signal governing traffic in said section, said signal having a pair of lamps each having a filament, said lamps when both illuminated providing one signal aspect, a first and a second control winding, and means controlled by traffic conditions in said section for energizing one of 20 said lamp filaments in series with one of said control windings and for also energizing the other of said lamp filaments in series with the other of said control windings, said signal having a third lamp, and means controlled by said control windings for controlling the supply of current to said third lamp, said control windings also controlling the circuits for energizing said 25 pair of lamps.

30 19. In combination, a section of railway track, a signal governing traffic in said section, said signal having a pair of lamps each having a filament, said lamps when both illuminated providing one signal aspect, a first and a second control winding, a first supply circuit for energizing the filament of one of said lamps in series with one of said control windings, a second supply circuit for energizing the filament of the other of said lamps in series with the other of said control windings, means controlled by traffic 35 conditions in said section for energizing said first and second supply circuits, means controlled by traffic conditions in advance of said section for energizing the filament of one of said lamps by a third supply circuit shunting the control 40 winding associated with said lamp filament, said signal having a third lamp, and means controlled by said control windings for controlling the supply of current to said third lamp.

45 20. In combination, a section of railway track, a signal governing traffic in said section, said signal having a pair of lamps each having a filament, said lamps when both illuminated providing one signal aspect, a first and a second control winding, a first supply circuit for energizing the filament of one of said lamps in series with one of said control windings, a second supply circuit for energizing the filament of the other of said lamps in series with the other of said control windings, means controlled by traffic 50 conditions in said section for energizing said first and second supply circuits, means controlled by traffic conditions in advance of said section for energizing the filament of one of said lamps by a third supply circuit shunting the control winding associated with said lamp filament, said signal having a third lamp, and means controlled by said control windings for controlling the supply of current to said third lamp, said control windings also controlling said first and second supply 55 circuits.
